UNITED STATES PATENT OFFICE

2,439,403

VARIABLE INDUCTIVE TUNER

Charles J. H. Victoreen, Dayton, Ohio

Application January 8, 1944, Serial No. 517,517

2 Claims. (Cl. 171—242)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to improvements in device for tuning radio frequency amplifiers.

It is an object of the invention to provide a device for tuning simultaneously a multiplicity of circuits in a radio frequency amplifier, said device extending the range of inductance of the amplifier circuit by adjusting a variable slug 23 with sections having different permeabilities.

A further object is the provision of a device for simultaneously tuning a multiplicity of circuits in a radio frequency amplifier and at the same time providing a band-width adjustable from a few kilocycles to several megacycles.

A further object is the provision of a device for varying the inductance of a circuit by sliding in a coil a core having a plurality of sections with different permeabilities.

A further object is the provision of a novel device for wide range tuning of a tuned radio frequency amplifier in which the desired characteristics are obtained by the use of ganged inductive tuning for a plurality of stages of radio frequency amplification. In accordance with the invention, the tuning is accomplished by sliding cores of different permeabilities within the inductance coils of the interstage transformers of the amplifier. The cores are ganged by being mounted in tandem on a single rod, which enables all of the cores to be moved simultaneously.

These and other objects are attained by the novel structure and arrangement hereinafter described and illustrated by the accompanying drawings, in which

Fig. 1 is a plan view of a device embodying the invention.

Fig. 2 is a plan view of the device with the cover removed.

Fig. 3 is a side elevational view of the device.

Fig. 4 is a sectional view taken on the line 4—4 of Fig. 1.

Fig. 5 is a sectional view taken on the line 5—5 of Fig. 4.

Referring to the drawings, there is shown a casing having a lower section 1 and an upper section or cover 2, the casing being divided into a plurality of shielded compartments 3 in which are mounted interstage transformers. Positioned in each compartment are supporting frames 15 upon which are mounted cylindrical coil forms 17 of thin insulating material upon which are closely interwound the primary and secondary 55 windings 19 and 20 of the transformers.

The tube plate and grid capacities (not shown) normally supply the capacities with which the primary and secondary coil windings 19, 20 respectively are resonant. Also on the form 17 is 60

provided a tertiary winding 21 which is series resonant with a variable mica capacitor 16, the capacity of which can be adjusted by a screw 26. By adjusting the tertiary circuit, the band width of the transformer can be controlled.

Extending through forms 17, which are hollow and coaxial, and through the compartments 3, is an adjustable core 4. The core 4 is composed of a succession of slugs 22, 23, 24 mounted on a continuous rod 25. Slugs 22 are of polyiron or other ferromagnetic material, slug 23 is of brass or similar nonferrous materials, and slug 24 is of a dielectric. The polyiron slug 22 and the brass slug 23 are partly cylindrical, fitting snugly within coil forms 17 and partly tapered on one pair of adjoining ends. The dielectric slugs 24 are also cylindrical on their outer surfaces, filling out the spaces around the tapered portions of slugs 22, 23. This construction produces an overall cylindrical structure for core 4 so that it slides smoothly within the forms 17.

Supported by an end wall of the casing is a threaded shaft 5 on which rides a nut 12, fixed to a sleeve 27, which in turn is fixed to rod 25. The sleeve 27 has a slot 28 and is prevented from rotation by means of a post 29 positioned in the slot 28. By rotating shaft 5, the sleeve 27 and the rod 25 are caused to move longitudinally.

The extreme range of tuning is effected by starting with the cylindrical portion of the polyiron slug 22 wholly within the coil form 17. This is the position of maximum inductance and lowest frequency. As the tapered portion of the polyiron is slid into the coil form 17, inductances of the coils 19, 20, 21 are reduced smoothly and more or less linearly. When the tapered brass core begins to enter the coils, the inductance is reduced still further, through the action of induced currents in the brass; and minimum inductance is reached when the brass slug fills the coil form. By properly adjusting the tapers of slugs 22 and 23, and by providing, for example, a small gap between the two slugs, the tuning can be made quite linear with the insertion of the rod in the coils.

In order to provide a trimmer adjustment to line up all the stages initially and to allow for variation of capacity from tube to tube, an adjustment is provided for shifting independently each supporting frame 15 along the axis of the core 4. In each compartment a screw 30 is prevented from longitudinal movement by a nut 31 and spring washer 32. The screw 30 threadedly engages a nut 33 which engages a U-shaped member 34 having one leg longer than the other. The long leg of member 34 engages the upper surface of nut 33 and the shorter leg engages the side of the nut. (See Fig. 4.) The member 34 is pivotally mounted at 6 and has integral therewith right angularly directed legs 37 carry-

ing pins 36 in a slot 35 of a bracket 38 fixed to the support 15 which is mounted for sliding movement along the lower section 1 of the casing. (See Fig. 5.) By rotating the screw 30, the support 15 is moved horizontally. The slots 35 prevent binding of the pins 36, and the snug cross-wise fits of the pins in the slots 35 hold the frames 15 firmly in adjusted positions and preserve the necessary stability of the amplifier.

The above description is to be considered as illustrative and not limitative of the invention of which modifications can be made obviously without departing from the spirit and scope of the invention as set forth in the appended claims.

The invention having been described, what is claimed is:

1. In an adjustable inductance device having a casing, a plurality of frames adjustably carried by the casing, coil means carried by each frame, a core for each coil means, and means carried by the casing for supporting and for simultaneously moving all the cores with respect to the frames; means for adjusting the position of an individual frame with respect to its core comprising a screw carried by the casing, a nut on the screw, a linkage having one end connected to the nut and the other end to the frame, so that rotation of the screw changes the position of such individual frame with respect to its core.

2. In a tuning device for radio apparatus: a casing containing a plurality of frames each slidably mounted in the casing; a plurality of tuning means, each corresponding to one of the frames and including two parts which are moved relatively to each other to accomplish tuning, one of the parts being carried by the casing and the other by the frame; and position-adjusting means for each frame, these position-adjusting means including a screw supported by the casing together with a nut and linkage controlled by movement of the screw for adjusting the position of each frame with respect to the casing.

CHARLES J. H. VICTOREEN.
